J. A. CAMERON AND G. B. BIRCH.
SLITTING AND REWINDING MACHINE.

APPLICATION FILED FEB. 5, 1917.

1,314,786.

Patented Sept. 2, 1919.

UNITED STATES PATENT OFFICE.

JAMES A. CAMERON AND GUSTAF BIRGER BIRCH, OF BROOKLYN, NEW YORK, ASSIGNEES
TO CAMERON MACHINE COMPANY, OF BROOKLYN, NEW YORK, A CORPORATION OF
NEW YORK.

SLITTING AND REWINDING MACHINE.

1,314,786.

Specification of Letters Patent. Patented Sept. 2, 1919.

Application filed February 5, 1917. Serial No. 148,569.

To all whom it may concern:

Be it known that we, JAMES A. CAMERON and GUSTAF B. BIRCH, citizens of the United States, and residents of the borough 5 of Brooklyn, in the county of Kings, city and State of New York, have invented certain new and useful Improvements in Slitting and Rewinding Machines, of which the following is a specification.

This invention relates to slitting and rewinding machines and in particular to the slitting mechanism designed for use in connection with such machines.

In the art of slitting and rewinding sheet material, such as paper, fabric, metal foils, and the like, one of the more successful types of machines embodies the mechanism shown generally in Patent No. 1,076,189, in which a pair of rewinding rolls in direct peripheral 20 and supporting engagement with the rewound coils, coöperate with a third roll engaging the upper periphery of the coils to rotate the coils and thereby perform the rewinding operation. In the machine 25 shown in the patent referred to, one of the rewinding rolls on which the rewound coils are supported is utilized also as a cutter roll and for this purpose is provided with a cylindrical shell having a glass-hard surface 30 against which are pressed a series of cutting disks which operate to slit an interposed moving web in a manner well-known in the art. Because of the great difficulty of uniformly and properly hardening the surface 35 of a large cylinder, it has been found advisable to form the cylindrical shell of the cutter roll in sections, as has been pointed out in the aforesaid patent and, furthermore, to restrict as far as possible the diameter 40 of the cutting roll. With the development of the art, however, a point has been reached in which a cutter roll having a diameter small enough to comply with the limitations of the hardening process cannot 45 be used as a supporting roll for the rewound coils because of its tendency to bend under the weight of the coils and thereby interfere with both the slitting and the rewinding operations. An object of this invention is 50 to provide rewinding rolls which will adequately support the rewound coils without bending, and to secure this result without increasing the diameter of the cutter roll.

Another feature of the invention is to pro-

vide means for preventing the flexure of 55 the cutter roll.

With these and other objects in view the invention consists principally in removing the cutter roll from coil supporting position and in providing a pair of coil supporting 60 rewinding rolls of such relatively large diameter that they can perform the function of supporting the rewound coils without bending. The relatively slender cutter roll may be provided with a backing roll adapted 65 to prevent bending of the cutter roll as shown in Figs. 1 and 2 of the drawing or the backing roll may be omitted as shown in Fig. 3. Other features of the invention will be referred to as the description proceeds. 70

In the accompanying drawing there is illustrated a preferred embodiment of the invention, but it is to be understood that the invention may be carried out by other embodiments and by mechanism differing from that selected for illustration. In the drawings, in which like reference characters are used to designate like parts,

Figure 1 is a diagrammatic view of a 80 device showing a preferred embodiment of the invention in which the cutter roll is mounted beneath the rewinding rolls and provided with a thrust receiving roller.

Fig. 2 is a diagrammatic view of a modification 85 in which the cutter roll is mounted in a location spaced apart from the rewinding rolls.

Fig. 3 is a view of a modification similar to that shown in Fig. 1 with the thrust roll 90 omitted.

In the particular embodiments of the invention disclosed there is shown a slitting and rewinding machine of the general type in which a pair of surface rewinding rolls 95 support the rewound coils and coöperate with a third roll engaging the upper surface of the coils to perform the winding operation. As has already been pointed out a well-known method of performing the slitting operation consists in using one of the coil supporting rewinding rolls to serve as a cutter roll with which a series of cutting disks coöperated to slit the web. In this particular instance coil supporting rewinding rolls of relatively large diameter are employed and, in lieu of adapting one of these rolls to serve also as a cutter roll, a special 100 105

cutter roll is provided which serves as a guide and cutter roll and takes no part in the coil supporting function. In the preferred embodiment of the invention the cutter roll 5 is mounted beneath the rewinding rolls and, in order to prevent flexure thereof, a backing roll is interposed between the rewinding and the cutter rolls in direct engagement with the peripheries thereof. In another 10 modification the cutter roll is located at a point separated from the rewinding rolls and is in this location also provided with a backing roll which will overcome any tendency that the cutter roll might have to 15 bend under the strain of the cutting operation. In still another modification a cutter roll is mounted beneath the rewinding rolls and the backing roller is omitted.

In the embodiment of the invention shown 20 in Fig. 1 of the drawing, the rewinding mechanism comprises the surface rewinding rolls 1 and 2 which are constructed with diameters of such a size that they will form an adequate and rigid support for the 25 rewound coils 3, and that the rewinding roll 2 will withstand the strain produced by the pull on the web 4 as it passes around the rewinding roll 2 and is fed directly to the periphery of the rewound coils 3. The 30 rewinding shaft 5 forms a core for the rewound coils and is so mounted in the machine that it is free to rise as the diameter of the coils increases. As will be evident, the coil supporting rolls 1 and 2 are rotated in the 35 same direction, and preferably coöperate with a driven rewinding roller 6 resting on the top of the rewound coils 3 to rotate the interposed coils, by their peripheral engagement therewith. The roller 6 is pref- 40 erably mounted in carriages, one of which is indicated at 7, that are adapted to move upwardly along the vertical guide members 8 in accordance with the increase in size of the rewound coils. This construction fol- 45 lows in a general way the construction shown in the patent to which reference has already been made, as well as that disclosed in application Serial No. 135,947, filed De- cember 9, 1916.

50 Instead, however, of making the cutter roll serve also as one of the supporting rolls 1 or 2 as in the patent, provision has been made for mounting this roll, because of the desirability of restricting its diameter 55 within certain limits, in a location where it will not be put to the strain of supporting the weight of the rewound coils. Accordingly, in the embodiment of the invention shown in Figs. 1 and 3 of the drawing, the 60 cutter roll 9, which as can be seen, is of relatively small diameter as compared with the large rewinding rolls 1 and 2, has been mounted beneath and equi-distant from the rewinding rolls 1 and 2.

65 It has been found when operating on cer-

tain materials that the cutter roll 9 dis- 70 plays a tendency to bend not only under the weight of the rewound coils, but the cutter roll is also inclined to bend under the upward pressure of the web 4 which in the cases where the largest sized mill rolls 10 are being handled, is very great. In order to counteract this upward bending of the cutter roll 9, a backing roller 11 may be interposed between the rewinding rolls 75 1 and 2 and the cutter roll 9 as shown in Fig. 1. The backing roller 11 is of such a size that it makes direct contact with the peripheries of the three rolls and thus forms a buffer connection that will resist the in- 80 ward thrust of any roll of the group toward the others. It will be seen that by this construction the upward bending of the cutter roll 9 due to the pressure of the web 4 is effectually eliminated and a rigid back- 85 ing member is thereby presented to the action of one or more cutting disks such as are indicated at 12.

It will be obvious that a construction such as is shown in Fig. 3, with the thrust roller 90 11 omitted, is within the scope of the invention. In such a construction the down- 95 wardly acting force of gravity on the cutter roll would be sufficient to counteract the upward web pressure exerted when web 95 rolls of moderate weight and size are being operated upon.

While the most important feature of the structural arrangement shown in Fig. 1 is the prevention of bending of the cutter roll 100 9, it will be evident that the same construction tends also to resist any tendency to bend that might occur in the case of the re- 105 winding roll 2. The general triangular ar- 110 rangement of the rewinding rolls 1 and 2 and the cutter roll 9, supplemented by the action of the interposed backing roller 11, is such that any given roll resists inward pressure with what is practically the resist- 115 ance of all the rolls in the group, and a compact structure is secured which can most effectively resist pressure which, as can be seen, is applied from practically all sides.

In the modification of the invention shown in Fig. 2, the rewinding mechanism shown in Fig. 1 is again employed, but the cutter roll is shown in a position spaced away from the rewinding rolls 1 and 2. The backing roller 11 is retained and is shown as having a larger diameter than in Fig. 1 since in 115 this case the backing roll must be self-sup- 120 porting and is not supplemented by the re- 125 winding rolls 1 and 2. This construction while lacking the compact, thrust resisting arrangement shown in Fig. 2, is more easily accessible than the corresponding structure and may be more suitable for certain classes of work.

For insuring the complete severance of the web and separating the strips a separator 130

13 may be employed which in Fig. 1 is shown as supported by the arm 14 which carries the cutting disk 12. In order to obviate the possibility of the adherence of 5 the strips to the cutter roll 9 and thereby fouling the same, a stripper plate, or doctor, 15 is so mounted as to engage the surface of the cutter roll closely adjacent the point where the slotted web leaves the surface of 10 the roll.

As is the case in the application referred to, the cutter roll 9 and consequently the cutting disks 12 which are driven by their engagement therewith, are rotated at a peripheral speed slightly exceeding the speed 15 of travel of the web to insure the effective slitting of the web. In the operation of the device the rewinding roll 2, which determines the speed of travel of the web may be 20 rotated at a peripheral speed of, for instance, 101 feet per minute while the rewinding roll 1 and the cutter roll 9 may each rotate at a peripheral speed of 102 feet per minute. The difference in the rates of speed may, of 25 course, be greater, and in some circumstances it may be desirable to rotate the cutter roll at a higher peripheral speed than either of the rewinding rolls 1 or 2. As has been stated, the rewinding roll 1 is driven at a peripheral speed slightly exceeding that of 30 the rewinding roll 2, and in turn the rewinding roll 6 is driven still faster than the rewinding roll 1 to facilitate the compact winding of the coils. The rewinding roll 1 35 is preferably driven from the roll 2 through a gear 16 carried by the roll 2 which meshes with an intermediate gear 17 which meshes in turn with a gear 18 carried by the roll 1. The gear 18 also meshes with an intermediate 40 gear 19 which meshes with a gear 20 to drive the cutter roll 9. It will be seen that the web passes over the guide rollers 12 and 22 into engagement with the rewinding roll 1, which, since its peripheral speed exceeds 45 the speed of travel of the web, effects to some extent a smoothing action on the web preparatory to the slitting operation.

While the rewinding rolls and the cutter roll have been referred to as being driven at 50 different peripheral speeds, it is to be understood that they may be arranged to be driven at equal speeds, or the cutter roll 9, and rewinding roll 2 may be driven at the same speed and the rewinding roll 1 at a higher 55 speed as the conditions of the work may require.

What is claimed, is:

1. A slitting and rewinding machine comprising: a pair of surface rewinding rolls on 60 which the rewound coils are supported, a cutter roll mounted beneath the rewinding rolls, means for causing the web to engage one of the rewinding rolls, thence pass to the cutter roll, and from the cutter roll pass 65 around the other rewinding roll to the re-

wound coils, and slitting means engaging with the cutter roll.

2. A slitting and rewinding machine comprising: a pair of surface rewinding rolls for supporting the rewound coils, a cutter 70 roll mounted beneath the rewinding rolls, means for causing the web to engage one of the rewinding rolls before it passes to the cutter roll, and slitting means engaging with the cutter roll. 75

3. A slitting and rewinding machine comprising: a pair of surface rewinding rolls of relatively large diameter for supporting the rewound coils, a cutter roll of relatively small diameter mounted beneath the rewinding 80 rolls, means for causing the web to engage one of the rewinding rolls before it passes to the cutter roll, and slitting means engaging with the cutter roll.

4. A slitting and rewinding machine comprising: a pair of rewinding rolls for supporting the rewound coils, a cutter roll mounted beneath and intermediate the rewinding rolls, cutting disks coöperating with the cutter roll to slit the web, means for 85 causing the web to engage one of the rewinding rolls before it passes to the cutter roll, and means for rotating said last-named rewinding roll at a higher peripheral speed than the speed of travel of the web. 95

5. A slitting and rewinding machine comprising: a pair of surface rewinding rolls for supporting the rewound coils, a cutter roll mounted beneath and intermediate the rewinding rolls, cutting disks coöperating with the cutter roll to slit the web, means for causing the web to engage one of the rewinding rolls before it passes to the cutter roll, and means for rotating the cutter roll and the cutting disks at a higher peripheral speed 105 than the speed of travel of the web. 110

6. A slitting and rewinding machine comprising: a pair of surface rewinding rolls for supporting the rewound coils, a cutter roll mounted beneath and intermediate the rewinding rolls, means for causing the web to engage one of the rewinding rolls before it passes to the cutter roll, means for rotating said last-named rewinding roll and said cutter roll at a higher peripheral speed than the 115 speed of travel of the web, and slitting means engaging with the cutter roll.

7. A slitting and rewinding machine comprising: a pair of surface rewinding rolls of relatively large diameter for supporting the 120 rewound coils, a cutter roll of relatively small diameter mounted beneath and intermediate the rewinding rolls, means for causing the web to engage one of the rewinding rolls before it passes to the cutter roll, means for rotating said last-named rewinding roll at a higher peripheral speed than the speed 125 of travel of the web, and slitting means engaging with the cutting roll.

8. A slitting and rewinding machine comprising:

- 4
- prising: a pair of surface rewinding rolls of relatively large diameter for supporting the rewound coils, a cutter roll of relatively small diameter mounted beneath and intermediate the rewinding rolls, means for causing the web to engage one of the rewinding rolls before it passes to the cutter roll, means for rotating the cutter roll at a higher peripheral speed than the speed of travel of the web, and slitting means engaging with the cutter roll.
9. A slitting and rewinding machine comprising: a pair of surface rewinding rolls of relatively large diameter for supporting the rewound coils, a cutter roll of relatively small diameter mounted beneath and intermediate the rewinding rolls, means for causing the web to engage one of the rewinding rolls before it passes to the cutter roll, means for rotating said last-named rewinding roll and said cutter roll at a higher peripheral speed than the speed of travel of the web, and slitting means engaging with the cutter roll.
10. A slitting and rewinding machine comprising: a pair of surface rewinding rolls on which the rewound coils are supported, a cutter roll mounted beneath the rewinding rolls, one of said rewinding rolls being driven at a higher peripheral speed than the other, means for causing the web to engage the rewinding roll having the higher peripheral speed, thence pass to the cutter roll, and from the cutter roll pass around the other rewinding roll to the rewound coils, and slitting means engaging with the cutter roll.
11. A slitting and rewinding machine comprising: a pair of surface rewinding rolls on which the rewound coils are supported, a cutter roll mounted beneath the rewinding rolls, said cutter roll and one of said rewinding rolls being driven at a higher speed than the other rewinding roll, means for causing the web to engage the rewinding roll having the higher speed, thence pass to the cutter roll, and from the cutter roll pass around the other rewinding roll to the rewound coils, and slitting means engaging with the cutter roll.
12. A slitting and rewinding machine comprising: a pair of surface rewinding rolls spaced apart, located in the same horizontal plane and rotating in the same direction, a rewinding shaft, for the rewound material, above the rewinding rolls and intermediate the latter, a cutting roll below the rewinding rolls and intermediate the same, a cutter coating with the cutting roll, and means for rotating the cutting roll and the rewinding rolls in the same direction.
13. A slitting and rewinding machine comprising: a pair of surface rewinding rolls rotating in the same direction and adapted to support the rewound coils, a cutter roll mounted beneath the rewinding rolls and intermediate the same, means for driving one of the rewinding rolls at a certain peripheral speed, means for driving the other rewinding roll at a higher peripheral speed, and slitting means engaging with the cutter roll.
14. A slitting and rewinding machine comprising: a pair of surface rewinding rolls rotating in the same direction and adapted to support the rewound coils, a cutter roll mounted beneath the rewinding rolls and intermediate the same, means for driving one of the rewinding rolls at a certain peripheral speed to determine the speed of travel of the web, means for driving the cutter roll at a higher peripheral speed than the speed of travel of the web, and slitting means engaging with the cutter roll.
15. A slitting and rewinding machine comprising: a pair of surface rewinding rolls on which the rewound coils are supported, a cutter roll mounted beneath the rewinding rolls, a backing roll interposed between the cutter roll and the rewinding rolls, and slitting means engaging the cutter roll.
16. A slitting and rewinding machine comprising: rewinding mechanism, a cutter roll, cutting members adapted to engage the surface of the roll to slit the web, and a backing member in engagement with the cutter roll.
17. A slitting and rewinding machine comprising: a surface rewinding roll on which the rewound coils are supported, a cutter roll, a backing roll interposed between the rewinding roll and the cutter roll, and slitting means engaging with the cutter roll.
18. A slitting and rewinding machine comprising: rewinding mechanism, a cutter roll arranged to alter the course of travel of the web, a backing member in engagement with the cutter roll, and slitting means engaging with the cutter roll.
